GEORGE LINCOLN PREBLE, OF LYNN, MASSACHUSETTS, ASSIGNOR TO PARCO SPECIALTY CO., OF LYNN, MASSACHUSETTS, A CORPORATION OF MASSACHUSETTS

RIBBON COVERING MACHINE

Application filed November 7, 1927. Serial No. 231,439.

This invention relates to a method and apparatus for applying a temporary covering strip to an adhesively coated ribbon or the like.

- 5 The apparatus and method are of general application, but are particularly adapted to use in conjunction with a machine disclosed in the copending application of Sinius M. Hansen, Serial No. 127,048, filed August 4, 1926. This machine is suitable for producing adhesively coated strips for a wide range of purposes, being particularly adapted to the production of partially coated ribbon to be applied to shoe uppers and the like, ribbon 10 of this character being specifically disclosed in Patent No. 1,618,809 and Patent No. 1,618,754. It is advantageous to cover the plastic adhesive material with a temporary covering strip which preferably consists of 15 inexpensive, and comparatively yieldable or loosely woven fabric. Thus the agglutinant is protected against accidental engagement with foreign objects and its original powers of adhesion are maintained for a long period 20 of time. Since the ribbon or fabric which carries the adhesive coating is formed of closely woven material that is not as easily stretched or deformed, it has heretofore been rather difficult to apply the temporary coating strip to the adhesive material and to have the same remain permanently in place due to the widely varying characteristics of the two fabrics. 25 Thus the strip which has been somewhat stretched during the coating operation and which normally has considerable elasticity within certain limits, has tended to draw away from the covering strip and to cause puckering of the same. 30 The apparatus more particularly forming the subject matter of the present invention is designed to overcome these difficulties and to apply the strip to the adhesive coating in such a manner that the fabric elements may 35 remain in permanent engagement with each other. While this apparatus may be used in a wide variety of environments and for various analogous purposes, it is particularly adapted for use in conjunction with the machine disclosed in the above identified appli- 40 cation of Sinius M. Hansen and as disclosed herein forms a part of that machine. Thus the adhesive coating has not fully reached its condition of permanent plasticity when the covering fabric is applied thereto. In other 45 words, the plastic or viscous agglutinant is applied to one portion of one face of the ribbon and a certain amount of moisture is removed therefrom before the covering strip is applied. However the agglutinant has not 50 yet attained its normal permanent condition when the covering strip is applied thereto. In order to conform to the widely different characteristics of the base fabric and the covering strip, I provide mechanism to cast 55 considerable tension upon the covering strip and to direct the latter along a path which converges with the path of the ribbon. 60 I have found that the application of the covering strip to the coated ribbon is particularly effective when the strip is carried directly around a curved surface, such as the peripheral portion of the roller, and when the ribbon is engaged with the outer face 65 of the covering strip as so disposed. I also 70 prefer thence to conduct the superimposed elements to yieldably mounted factors which are effective in still further pressing the ribbon and strip into firm adhesive engagement, while aiding in the maintenance of a com- 75 paratively tight wrap about the roller. Preferably the covering strip may be nar- 80 rrower than the partially coated ribbon and as a consequence, in the preferred embodiment of my invention, the covering strip is 85 guided toward that portion of the ribbon which is adhesively coated.

The above and further objects and advantageous features of the invention will be apparent to those skilled in the art upon a reading of the subjoined description and claims in conjunction with the accompanying drawings, in which

Fig. 1 is a side elevational view of a machine embodying the apparatus which more particularly forms the subject matter of this invention;

Fig. 2 is a detailed plan view of the braking mechanism for casting tension upon the cov- 95 ering strip;

Fig. 3 is a side elevational view of the apparatus;

Fig. 4 is an end elevation of the braking mechanism disclosed in Fig. 2;

Fig. 5 is a top plan view of the assembly shown in Fig. 3; and

Fig. 6 is a section on line 6—6 of Fig. 3.

10 While the apparatus which represents the specific embodiment of the present invention may be used in conjunction with a wide variety of mechanisms and for various purposes, it is especially advantageous when used in conjunction with a machine for adhesively coating ribbon or the like, preferably being arranged to receive the adhesively coated fabric when the agglutinant has partially dried and to effect the engagement of the covering strip and the ribbon under these conditions.

20 Accordingly Fig. 1 illustrates this apparatus, indicated in general by the symbol A, when used in conjunction with a machine of the character disclosed in the above identified copending application. This machine 25 comprises in general apparatus G for applying adhesive material, which preferably may be permanently plastic, to a strip of ribbon 40 which may come from any suitable source such as the spool 30. The agglutinant is contained 30 within the receptacle 10 and is supplied thereby to the factor G. From the latter the ribbon passes to the drying factor D which comprises a large drying roll 45 and a co-operating grooved roll 46. These rolls receive 35 a large number of turns of the ribbon and, when rotated at a moderate speed, are effective in exposing each portion of the ribbon to the air for a considerable period of time. Preferably the roll 45 may be provided 40 with suitable heating elements such as electric resistance members in order to aid the drying effect. From the roll 45 the ribbon passes to rolls 70 and 71, whence it goes upwardly to the mechanism A more particularly forming the subject matter of the 45 present invention. This mechanism is supported upon an upright 140 secured to the table 1. The various rotatable rolls etc. of the machine and the apparatus A are driven 50 by the electric motor 2 through the belt 82 and suitable belts, pulleys and the like, the apparatus A being driven by a belt 120 which extends upwardly from a pulley 193.

55 Figs. 3 and 5 show in greater detail the mechanism for applying the covering strip to the adhesively coated ribbon. This mechanism is adapted to receive the ribbon 40 from the roll 70 while the covering strip 121 is received from a spool 122 which is provided with a suitable friction brake 123 of 60 resilient material to retard the movement of the spool or to place a drag upon the covering strip.

A suitable braking mechanism 124, Figs. 2 and 4, is located between spool 122 and the

point where the covering strip and ribbon meet, in order to cast still further tension upon the covering strip. This braking mechanism comprises a supporting bracket 125 and a pair of friction members or shoes 126, each of which comprises a yieldable block 127 of soft rubber or the like which is covered with suitable fibrous material 128 that has a comparatively high coefficient of friction. The shoes are mounted upon the stud 119 which is provided with a head 129 and a thumb nut 130 in order to adjust the degree of compression imposed by the spring 131, the latter being located between the thumb nut and one of the friction elements 132 yieldably to urge these elements toward each other. Normally strip 121 is passed between the elements and is thus subjected to considerable friction. This is highly desirable since the tape 40 is being stretched somewhat due to its arrangement in relation to the several tape carrying rolls of the machine. It is thus essential to stretch the fabrics corresponding amounts in order to permit their continued intimate engagement when they 133 are released from tension.

The ribbon and strip are preferably brought into superimposed engagement upon the periphery of roll 139 so that the latter is directly contacted with the surface of that roll while the coated portion of the former is superimposed upon the covering strip, this arrangement being particularly effective in insuring the continued intimate engagement of the covering strip and adhesive after the coated ribbon leaves the machine. The combined ribbon and covering strip are wrapped upon a considerable peripheral portion of roll 139 and thence pass between rolls 147 and 148, the former being rigidly supported upon the arm 158 which extends outwardly from bracket 142 and the latter being mounted upon the outer end of the arm 182 which is pivotally connected

with the bracket, as designated by numeral 183.

The roller 148 is provided with suitable flanges 187 which are juxtaposed to opposite faces of roller 147 and are adapted to cooperate with the face of each roller in providing a guideway therebetween for the combined ribbon and covering strip. A suitable resilient element 189 such as a rubber band 10 serves normally to draw the outer end of arm 182 towards the fixed roller 147. Thus the peripheries of rolls 147 and 148 are yieldably urged toward each other and serve still further in pressing the ribbon and covering strip 15 in firm adhesive engagement with each other. The roller 147 is driven by a belt 195 which engages pulleys fixed to roll 139 and roll 147 respectively, thus serving to throw a suitable tension upon the combined ribbon and covering strip, as these elements pass from roll 149. It is evident that apparatus of the character disclosed herein may be used in a wide variety of environments when it is desired to provide a temporary covering strip for an adhesively coated portion of a sheet. While for purpose of illustration and description, I have referred particularly to a ribbon and a covering strip it is obvious that the width and character of these elements may be varied 20 widely and consequently I intend the following claims to be read in accordance with the possible equivalent uses of this machine. It has been found that a machine of this character is particularly effective in applying a 25 loosely woven, yieldable covering fabric to an adhesive coating which has been applied to a ribbon of much closer texture, and experiments have shown that the wrapping of the ribbon and covering strip about a curved 30 surface such as the periphery of roll 139 is particularly effective in insuring the continued firm adhesive engagement of these elements and in avoiding the tendency of the 35 fabric elements to pucker and draw away 40 from each other which has otherwise been usual.

I claim:

1. Apparatus for applying a covering strip to a ribbon which has a portion adjoining one margin adhesively coated and the remainder uncoated, said apparatus comprising a guide passage for the ribbon, a guide passage of smaller width for the covering strip arranged to direct the strip toward the coated portion of the ribbon, and a roller adapted to receive the ribbon and strip wrapped thereabout in superimposed relation, a pair of rollers, means yieldably urging said rollers toward each other, said pair of rollers being arranged to receive therebetween the strip and ribbon as they leave the first named roller.
2. Apparatus for applying a covering strip to a ribbon which has a portion adjoining one margin adhesively coated and the remainder uncoated, said apparatus comprising

a guide passage for the ribbon, a guide passage of smaller width for the covering strip arranged to direct the strip toward the coated portion of the ribbon, means engaging the strip as it passes to the guide to impart a frictional drag to said strip, a roller adapted to receive the ribbon and strip wrapped thereabout in superimposed relation, a pair of rollers, and means yieldably urging said rollers toward each other, said pair of rollers being arranged to receive therebetween the strip and ribbon as they leave the first named roller.

3. Apparatus for applying a covering strip to an adhesively coated ribbon, comprising a guide for the ribbon, a guide for the covering, a roller, said guides being arranged to direct the ribbon and covering along converging paths which meet at the periphery of the roller, and a pair of rolls yieldably urged toward each other, said rolls and guides being arranged at opposite sides of the roller in such a manner that the ribbon and covering may be wrapped in superposed relation about a considerable portion of the circumference of the roller.

4. Apparatus for applying a covering strip to an adhesively coated ribbon, comprising a guide for the ribbon, a guide for the covering, a roller, said guides being arranged to direct the ribbon and covering along converging paths which meet at the periphery of the roller, a pair of rolls yieldably urged toward each other, said rolls and guides being arranged at opposite sides of the roller in such a manner that the ribbon and covering may be wrapped in superposed relation about a considerable portions of the circumference of the roller, and a friction brake adapted yieldably to grip the covering before it passes to its guide.

Signed by me at Lynn, Massachusetts, this 26th day of October, 1927.

GEORGE LINCOLN PREBLE.
